UNITED STATES PATENT OFFICE.

JOE KERSHAW, OF MENSTON, ENGLAND.

MACHINE OR APPARATUS FOR DYEING AND THE LIKE.

Application filed August 31, 1921. Serial No. 497,264.

To all whom it may concern:

Be it known that I, JOE KERSHAW, a subject of the King of Great Britain, residing at Rose Mount, Menston, Yorkshire, England, have invented new and useful Improvements in Machines or Apparatus for Dyeing and the like, of which the following is a specification.

This invention relates to machines or apparatus for dyeing, mordanting, bleaching, scouring or similarly treating with liquors or liquids wool, slubbing, yarn, wool and cotton wastes, woolen and cotton warps, hose, rags, jute and all raw materials in which the material under treatment is placed in a tank or vat between a movable perforated or the like false bottom and a stationary or fixed lattice or the like top and is repeatedly squeezed or compressed when saturated with the liquor or liquid and allowed to open out or expand after each compression and it relates particularly to the machine or apparatus described in the specification of United States Letters Patent No. 934543, granted to me, and the primary object of the present invention is in a machine or apparatus of this class the co-operation therewith of a liquor or liquid circulating device characterized by an external pump in conjunction with a bottom outlet and inlet pipe and longitudinal side or side and end outlet pipes located towards the top of the tank or vat but below the normal level of the liquor or liquid in the tank or vat and with a spraying device comprising perforated pipes attached to and located above the lattice or the like top and also, if desired, with a reserve tank. The invention also consists of the construction, arrangement and combination of parts embracing means for operating the movable false bottom comprising a falling-over weighted lever operated by an endless-chain device adapted to control the rotational direction and speed of a longitudinal shaft carrying the winding-drums for raising and lowering the false bottom, also means for raising the lattice or the like top from its stationary or fixed position comprising a hand operated cross shaft carrying the winding-drums or the like and controlled in the downward movement of the lattice or the like top by a ratchet-and-pawl device or devices, and also means for treating materials in the hank form comprising end plates attached to the lattice or the like top the said plates being provided with slots

through which the supporting laths or sticks are inserted.

In the accompanying drawings:

Figure 1 is a longitudinal elevation of my improved machine or apparatus.

Figure 2 is an end elevation of same showing the means for operating the movable false bottom more fully, and Figure 3 a sectional plan on the broken line *a—b*, Figure 1.

Figure 4 is a detail hereinafter referred to.

According to this invention in a preferred construction of the machine or apparatus as illustrated in the drawings I provide a wood tank or vat 2 of rectangular shape which is located partly above and partly below the ground level 3. The movable perforated or the like false bottom 4, preferably made in sections 5, is carried on a frame 6 loosely fitting the tank or vat. Vertical metal strips or guides 7 are provided on the inside of the tank or vat at the sides and ends to prevent the metal frame or the false bottom coming in contact with the wood sides and ends and thereby damaging same. The said frame is supported near each corner by vertical rods 8 connected at their upper ends to chains or wire ropes 9 by which the false bottom 4 is vertically reciprocated through mechanism 75 hereinafter described. The stationary or fixed lattice or the like top 10 is movably and adjustably secured within the top of the tank or vat, and to this end the said top is supported near each corner by vertical metal strips or flat bars 12 each provided with a series of longitudinally arranged holes 13 any horizontal set of which may be engaged by four pegs or pins passed through holes 14 in the sides of the tank 80 or vat. Other means may be provided for fixing the top in position within the tank such as, a cross bolt secured thereto near each end and adapted to move outwards by a hand lever the ends of same engaging holes 95 in the metal strips 7 fixed to the inside of the tank or vat at the sides.

A spraying device 15 is located above the lattice or the like top and secured thereto. This spraying device may consist of two horizontal pipes 16 each having perforations or holes at intervals along its length and closed at both ends. The pipes are coupled together by a branch pipe 17 which is coupled to a vertical pipe 18. Between these 105 horizontal pipes and the lattice or the like top is located a shallow tank or tray 20 pro-

vided with perforations in its bottom. The vertical pipe 18 fits telescopically a vertical supply pipe 21 in order to allow the top to be raised sufficiently high, by mechanism 5 hereinafter described, for the false bottom with the material under treatment resting thereon to be raised to the top of the tank or vat for the removal or inspection of the material.

- 10 The liquor or liquid is circulated by an external pump 22 located at one end of the tank or vat and by means of which the liquor or liquid can be passed through the material under treatment in either direction 15 without the necessity of reversing the pump in a very simple and efficient manner by an arrangement of pipes, branch pipes and valves. If desired a separate or reserve tank may be used in conjunction with the said 20 goods-tank. In a preferred arrangement in which a separate or reserve is used, a horizontal pipe 23 running beneath the bottom of the tank is open to the tank by means of a branch pipe 24 and is coupled to 25 the drain at one end said end being provided with a valve and at the other end coupled with the suction end of the pump 22 and provided with a three-way valve 25 at the junction thereof and to which junction a horizontal outlet pipe 26 from the bottom of the reserve tank is coupled. Coupled to the delivery end of the pump 22 and provided with a three-way valve 27 at the junction is a vertical supply pipe 35 21^a extending above the driving mechanism located above the tank and coupled to the vertical supply pipe 21, which is telescopically coupled to the vertical pipe 18 of the spraying device, by a horizontal branch pipe 21^b. A horizontal inlet or return pipe 28 to the top of the reserve tank is coupled to the vertical supply pipe 21^a and is provided with a three-way valve 29 at the junction thereof. A branch pipe 30 is coupled 40 at one end to the three-way valve 27 at the junction of the delivery end of the pump 22 and the vertical supply pipe 21^a and at the other end to the horizontal pipe 23 beneath the bottom of the tank. Horizontal 45 side or side and end pipes 31 are provided on the outside of the tank, said pipes communicating with the interior of the tank by means of branch pipes 33 and are connected to a common vertical pipe 34 the lower end 50 of which is coupled to the horizontal pipe 23 beneath the bottom of the tank between the three-way valve 25 at the suction end of the pump and the junction of the said branch pipe 30 with the same horizontal 55 pipe, the upper end of the vertical pipe 34 being coupled by a branch pipe 35 to the vertical supply pipe 21^a and is provided with a valve 36 at the junction and also a three-way valve 37 is provided at the junction 60 of the vertical pipe 34 with the horizontal 65 pipe.

tal pipe 23 beneath the tank. The outlet openings on the inside of the tank at the sides and at one end are provided with perforated plates in order to prevent the material being drawn through same. By opening certain valves and shutting off certain others or controlling same the liquor or liquid may be drawn from the bottom of the tank through the pump and forced up 70 through the vertical supply pipe and 75 through the spraying device in the form of streams through the perforations in the bottom of the shallow tank or tray 20, located between the spraying device 15 and the lattice or the like top 10, and through 80 the material in the tank, or same may be drawn from the sides and end of the tank and forced through the spraying device, or same drawn from the sides and end and forced into the bottom of the tank, or same 85 from the bottom and forced into the reserve tank, or same from the reserve tank and forced either through the spraying device or into the bottom of the tank.

The false bottom is raised slowly and 90 lowered rapidly from a driven cross shaft 40 journalled in brackets 41 secured to longitudinal beams 42 located above the tank and supported on and secured to end frames 43 located outside the tank and secured to 95 the ground foundation. To control the rotational direction and speed of the said cross shaft we employ preferably two sets of fast and loose pulleys mounted on said cross shaft, one set 44 of which is driven by 100 an open belt and the other set 45 at a greater speed by a crossed belt. The belts are moved on to their respective fast and loose pulley by means of forks 44^a and 45^a secured to a cross slide 46 mounted in bearings in 105 the brackets 41 carrying the driven cross shaft 40. This cross slide 46 is operated by a lever 47 suitably connected to same and secured on a longitudinal rocking shaft 48 mounted at one end in a bracket or hanger 110 49 secured to the longitudinal side beam 42 and at the other end in the end frame 43. Secured to this longitudinal rocking shaft is a dependent hand lever 50 provided with a counterpoised weight 51 and located on the 115 outside of the end frame. By moving this hand lever to the right or to the left the belts, which engage or drive loose pulleys when the hand lever is in a vertical position, may be made to drive a fast pulley on one 120 set and a loose pulley on the other set, or vice versa. The said hand lever is secured in its vertical position by a detachable pin passed through same and engaging a hole 52 in the end frame so that in this position the false bottom is stationary, the belts driving loose pulleys. The driven cross shaft 40 drives at a reduced speed a central longitudinal shaft 53 journalled in brackets 54 secured on the end frames 43 by means of a 125 130

worm wheel 55 secured to this longitudinal shaft and enclosed within a casing 56 mounted between two cross beams 57. The said worm wheel is engaged by a worm 58 on a short shaft 59 journalled in bearings in the said casing and this shaft is driven by a wheel 60 on same in engagement with a pinion 61 on the driven cross shaft. Secured to the central longitudinal shaft 53 are two drums 53^a to each of which are connected the ends of two of the chains or wire ropes 9 each of which passes over a guide pulley 62 pivoted to a bracket secured to the horizontal side beam and the other ends to their respective rods carrying the false bottom. The central longitudinal shaft 53 has a sprocket wheel 63 secured to it on the outside of the end frame and over this sprocket wheel and a guide sprocket wheel 64 located vertically below same and pivoted to the end frame or to a bracket 65 adjustably secured to same is stretched an endless chain 66. This chain is employed for automatically reversing the movement of the false bottom and to this end a lever 67 is secured on the longitudinal rocking shaft 48 on the inside of the frame. The end of this lever is slidably connected to a slotted link 70 pivoted at one end to one arm 71 of a three-armed lever secured to a short rocking shaft 72 passing through and mounted in bearings in the end frame and located on the inside of same. The other two arms are provided with weights the central one 73 with a large weight 74 for throwing over the lever on either side and the other arm 75 with a smaller counterpoise weight 76. On the other end of the short rocking shaft on the outside of the frame is secured a hand lever 77 the projecting end portion 78 of which is provided with a slot or fork which embraces the nearer portion or member of the stretched endless chain. Adjustable stops 80 are provided on this portion of the chain one at each side of the projecting slotted end portion of the lever. Figure 4 shows an enlarged section of the top stop in contact with the forked end portion 78 of the lever 77. The stops are slidably secured to the chain by the set-screws 80^a so that the distance between the stops may be altered thereby allowing a varied lift of the false bottom in order that different weights or bulks of material may be treated in the same machine or apparatus. In operation when the portion of the chain containing the stops 80 is moving upwards the bottom stop comes into contact with the downwardly projecting end and lifts same until the middle weighted arm becomes just past the vertical position when the weight on same falls freely over giving to same sufficient momentum to rock the longitudinal shaft 48 and thereby reverse the motion of the false bottom and at the same time

causing the portion of the chain to move downwards and at faster speed when the top stop comes into contact with the said lever which is now inclined upwards and raising the weighted arm until same is just past the vertical position when it falls over on the other side and thereby reverses the direction of the false bottom. In order to give the false bottom a dwell at the bottom of its stroke the top stop is moved further away from the bottom stop in which case the false bottom reaches the bottom of its stroke before the motion is reversed the chain thereby becoming slack during the remainder of the motion. The slotted or forked end portion 78 embracing the chain is pivoted to the lever 77 and secured rigid to same by a pin in order that same may be easily disengaged from the chain thus enabling the false bottom to be raised sufficiently high for the removal or inspection of the material under treatment.

The lattice or the like top is raised and lowered from a cross shaft 85 journalled in bearings in the side frame or to brackets 90 secured thereto. The shaft is turned by means of two handles 86 one at each end of same. A chain or wire rope 87 connected to each metal strip or rod secured to and supporting said top passes over guide pulley or pulleys 88 pivoted to a fixed bracket on the side beam and is connected at the other end to the said cross shaft or to a drum secured thereon. The top is prevented from falling when in a raised position by means of a ratchet and pawl arrangement 89.

In order to treat materials in the hank form the lattice or the like top is provided with attachment means for supporting the said hanks consisting of end plates 90 provided with vertical slots 91 through which the supporting laths or sticks are inserted. These parallel sticks are of rectangular shape in cross section and have recesses between their angles on the contact edges. The slotted end plates 90 are hung from and secured or removably secured to the lattice or the like top.

Steam for heating purposes is uniformly delivered at the bottom of the goods-tank and the reserve tank by means of a main steam pipe 92 having preferably forked extensions 93 running lengthwise along the bottom of the tank. Heated air for agitation purposes may likewise be uniformly delivered by means of an ordinary air injector in conjunction with the said steam pipe.

Claims:

1. In an apparatus of the class described, the combination of a vat, a vertically movable bottom therein, means for raising said bottom, and means automatically operated during said raising movement for reversing the direction of movement of the bottom.

2. In an apparatus of the class described, the combination of a vat, a vertically movable bottom therein, means for raising said bottom at slow speed, and means automatically operated during said raising movement to impart a downward movement to the bottom at an increased speed. 35
3. In an apparatus of the class described, the combination of a vat, a vertically movable bottom therein, a driven shaft supported for rotation above said vat, a countershaft geared to said driven shaft, cables connecting said bottom to said countershaft, an endless chain adapted to be operated by 40 the countershaft, means for changing the direction and speed of rotation of said driven shaft, and means carried by said endless chain for actuating said speed changing means. 45
4. In an apparatus of the class described, the combination of a vat, a vertically movable bottom therein, a driven shaft supported for rotation above said vat, two sets of fast and loose pulleys carried by said 50 shaft, one set adapted to rotate the shaft at a different speed from the other, a belt in engagement with each set of pulleys, one of said belts adapted to impart rotation in a direction opposite from that imparted by the other, a countershaft, means for transmitting motion from said driven shaft to said countershaft, cables connecting said bottom to said countershaft, a belt-shifter adapted 55 normally to retain one of said belts in engagement with a fast pulley and the other with a loose pulley, an endless chain in engagement with said countershaft, and means carried by said chain for actuating said belt shifter during rotation of the countershaft thereby to change the speed and direction of rotation of said shaft. 60
5. In an apparatus of the class described, the combination of a vat, a vertically movable bottom therein, a driven shaft supported for rotation above said vat, two sets of fast and loose pulleys carried by said shaft, one set adapted to rotate the shaft at a different speed from the other, a belt in engagement with each set of pulleys, one of said belts adapted to impart rotation in a direction opposite from that imparted by the other, a countershaft, means for transmitting motion from said driven shaft to said countershaft, cables connecting said bottom to said countershaft, a belt-shifter adapted 65 normally to retain one of said belts in engagement with a fast pulley and the other with a loose pulley, an endless chain in engagement with said countershaft, and means carried by said chain for actuating said belt shifter during rotation of the countershaft thereby to change the speed and direction of rotation of said shaft, said means being adjustable thereby to vary the periods of rotation in opposite directions. 65

In testimony whereof I have signed my name to this specification.

JOE KERSHAW.
